(57) CLAIM

The ornamental design for a hair coloring material holder for hair coloring apparatus, as shown and described.

DESCRIPTION

FIG. 1 is a perspective view of a hair coloring material holder for hair coloring apparatus showing my new design. FIG. 2 is a perspective view thereof, showing a single partition in phantom.

FIG. 3 is a perspective view thereof, showing two partitions in phantom.

FIG. 4 is a front view thereof.

FIG. 5 is a back view thereof.

FIG. 6 is an end view thereof, the opposite end view being a mirror image thereof; and,

FIG. 7 is a side view thereof, the opposite side view being a mirror image thereof.

The phantom lines are shown for illustrative purposes only and form no part of the claimed design.
